US00D925523S

(12) **United States Design Patent** (10) **Patent No.:** **US D925,523 S**
Andre et al. (45) **Date of Patent:** **** Jul. 20, 2021**

(54) **ELECTRONIC DEVICE**

- (71) Applicant: **Apple Inc.**, Cupertino, CA (US)
- (72) Inventors: **Bartley K. Andre**, Palo Alto, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Steven P. Jobs**, Palo Alto, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Douglas B. Satzger**, Menlo Park, CA (US); **Christopher J. Stringer**, Woodside, CA (US); **Eugene Antony Whang**, San Francisco, CA (US); **Rico Zörkendorfer**, San Francisco, CA (US)
- (73) Assignee: **Apple Inc.**, Cupertino, CA (US)
- (**) Term: **15 Years**
- (21) Appl. No.: **29/741,904**
- (22) Filed: **Jul. 16, 2020**

Related U.S. Application Data

- (60) Continuation of application No. 29/716,315, filed on Dec. 9, 2019, which is a continuation of application No. 29/592,800, filed on Feb. 2, 2017, now Pat. No. Des. 869,460, which is a continuation of application No. 29/473,938, filed on Nov. 27, 2013, now Pat. No. Des. 778,278, which is a continuation of application No. 29/467,655, filed on Sep. 20, 2013, now Pat. No. Des. 724,078, which is a continuation of application No. 29/432,301, filed on Sep. 14, 2012, now Pat. No. Des. 696,251, which is a continuation of application No. 29/432,307, filed on Sep. 14, 2012, now Pat. No. Des. 696,663, which is a continuation of application No. 29/432,242, filed on Sep. 14, 2012, now Pat. No.

Des. 690,298, which is a continuation of application No. 29/384,861, filed on Feb. 4, 2011, now Pat. No. Des. 673,948, which is a continuation of application No. 29/384,757, filed on Feb. 3, 2011, now Pat. No. Des. 675,612, which is a continuation of application No. 29/381,317, filed on Dec. 21, 2010, now Pat. No. Des. 674,383, which is a continuation of application No. 29/366,856, filed on Jul. 30, 2010, now Pat. No. Des. 633,092, which is a continuation of application No. 29/365,750, filed on Jul. 14, 2010, now Pat. No. Des. 633,090, which is a continuation of application No. 29/358,070, filed on Mar. 22, 2010, now Pat. No. Des. 629,799, which is a continuation of application No. 29/344,079, filed on Sep. 23, 2009, now Pat. No. Des. 624,072, which is a continuation of application No. 29/343,293, filed on Sep. 10, 2009, now Pat. No. Des. 620,004, which is a division of application No. 29/319,377, filed on Jun. 6, 2008, now Pat. No. Des. 602,016, which is a continuation-in-part of application No. 29/306,334, filed on Apr. 7, 2008, now Pat. No. Des. 602,015, which is a division of application No. 29/319,239, filed on Jun. 5, 2008, now Pat. No. Des. 615,083, which is a continuation-in-part of application No. 29/306,334, filed on Apr. 7, 2008, now Pat. No. Des. 602,015, which is a continuation-in-part of application No. 29/306,950, filed on Apr. 18, 2008, now Pat. No. Des. 600,241, which is a division of application No. 29/306,950, filed on Apr. 18, 2008, now Pat. No. Des. 600,241, which is a continuation-in-part of application No. 29/306,950, filed on Apr. 18, 2008, now Pat. No. Des. 600,241, which is a continuation of application No. 29/306,334, filed on Apr. 7, 2008, now Pat. No. Des. 602,015.

(57) CLAIM

The ornamental design for an electronic device, as shown and described.

DESCRIPTION

FIG. 1 is a bottom front perspective view of an electronic device showing the claimed design;
 FIG. 2 is a top rear perspective view thereof;
 FIG. 3 is a front view thereof;
 FIG. 4 is a rear view thereof;
 FIG. 5 is a left side view thereof;
 FIG. 6 is a right side view thereof;
 FIG. 7 is a top view thereof; and,
 FIG. 8 is a bottom view thereof.

The broken lines in the figures show portions of the electronic device that form no part of the claimed design.

FIG. 1

FIG. 2

FIG. 3

FIG. 4

FIG. 5

FIG. 6

FIG. 7

FIG. 8
